A. CARLSON.
WINDMILL AND OPERATING MECHANISM THEREFOR.
APPLICATION FILED APR. 10, 1915.

1,174,823.

Patented Mar. 7, 1916.

THE COLUMBIA PLANOGRAPH CO., WASHINGTON, D. C.

UNITED STATES PATENT OFFICE.

ALFRED CARLSON, OF KLAMATH FALLS, OREGON.

WINDMILL AND OPERATING MECHANISM THEREFOR.

Specification of Letters Patent. Patented Mar. 7, 1916.

1,174,823.

Application filed April 10, 1915. Serial No. 20,473.

To all whom it may concern:

Be it known that I, ALFRED CARLSON, a citizen of the United States, residing at Klamath Falls, in the county of Klamath and State of Oregon, have invented certain new and useful Improvements in Windmills and Operating Mechanism Therefor, of which the following is a specification.

The invention comprehends a novel wind mill governor or regulator automatically operable upon excessive wind pressure to move the driving wheel therefor into inoperative position.

It is also comprehended to employ brake instrumentalities which are automatically applied when the driving wheel is moved into inoperative position said brake instrumentalities coacting with the regulator aforesaid.

These and such other objects as may hereinafter appear are attained by the novel construction, combination and arrangement of parts to be hereinafter specifically described and claimed.

Reference will now be had to the accompanying drawings forming a part of this specification, wherein:

Figure 1 is a vertical sectional view through apparatus constructed in accordance with my invention. Fig. 2 is a horizontal sectional view, parts being broken away. Fig. 3 is a view in elevation of a set collar used in the regulator mechanism of this device. Fig. 4 is a vertical sectional view disclosing more clearly the operative connection for manually actuating the regulator member.

Throughout the following detail description and on the several figures of the drawings, similar parts are referred to by like reference characters.

Specifically describing my invention, the numeral 1 designates a casing of a suitable form and size to house the transmission gearing of my device, the casing being provided at one side with a cover 2 bolted or otherwise secured in position thereon. At its other side the casing is formed with a lateral extension 3 on which is rotatably mounted the driving member for the said gearing which, forming the subject matter of my copending application, Serial No. 58,212, filed October 27, 1915, is not herein specifically described. This driving member, in describing the particular embodiment of my invention, consists of the wind wheel 4 comprising the hub 5 composed of an inner and outer section bolted together by the fastening members 6 centrally thereof. This wheel is connected through its hub to the end of a drive shaft 8 revolvably mounted within a longitudinal bore of the extension 3. The inner side of the hub 5 is formed with a brake flange or drum 9 through which the rotation of the wind wheel 4 is controlled as will be more clearly apparent as this description proceeds.

The casing 1 is mounted upon the turntable 23 of any desired form for suitably supporting the driving mechanism hereinbefore set forth. In my wind mill construction which is suitably supported at the top of a conventional tower indicated 24 in Fig. 1, as is usual in devices of this type, I employ a governor control for the mechanism consisting of a rudder or vane 25 adjustably secured to an arm or lever 26 which in turn is secured to a horizontal shaft 27, journaled in the casing 1. The lever 26 is directly connected to the shaft 27 through the segmental gear 28 which intermeshes with a corresponding gear element 29 fastened on the shaft 30, the gear 29 having an opposing arm 31 secured thereto carrying a counterbalance weight 32 adjustable therealong. Extending laterally from the gear 28 is a roller bearing 33 which is adapted to coact with the cam extremity 34 of a slidable brake lever 35. This lever is slotted at one end and guided in its movements by the projection 36 on the casing 1 extending into the slot and said lever is pivotally connected at its other end to a lever 37 pivoted at 38 and carrying at opposite sides of its pivot opposing brake shoes 39, 39 coacting with the outer and inner faces of the brake drum 9 on the hub at the inner side of wheel 4, hereinbefore described. It may be further stated that the sliding brake lever 35 is normally held in its outermost position by means of a spring 40 pressing against the cam extremity, hence, normally maintaining release position of the brake shoes 39, 39.

It should be understood in referring to Fig. 1 that the governor parts 25, 26 and 31 occupy the dotted line or vertical positions under operative conditions of the mechanism. Thus the wind wheel 4 is always at work or in the wind so long as the wind pressure on said wheel is not abnormal, un-

less, of course, it is locked in inoperative position by manual means to be described hereinafter. In the aforesaid dotted position, it will be noticed that the rudder 25 is vertically disposed and set angularly on its supporting arm 26 so that when the wind reaches an abnormal pressure it will have a tendency to raise said vane from its vertical position to the horizontal position shown in full lines of Fig. 1 and in such position the area of operative wind surface on the wheel and rudder is overbalanced with respect to the vertical axis of rotation of the wind wheel support and naturally the wheel is moved rotatably on the turn table until its edge is in the face of the wind whereupon the wheel becomes inoperative as understood by those skilled in the art to which this invention refers. Immediately the excessive wind pressure falls the rudder 25 drops to its original vertical position adjacent to the turn table support, being actuated in its descent by the weighted arm 31 operatively connected thereto, which arm is also raised into horizontal position when the rudder is moved in the manner hereinbefore described. This action takes place automatically and obviously the driving wheel 4 is maintained in operation so long as its speed of rotation is not excessive such that it would be likely to injure the driving mechanism operated thereby. In the rising action of the rudder the roller bearing 33 on the segmental gear 28 with which the rudder is connected rides on the inclined cam extremity 34 of the brake lever 35 and as the roller descends on said incline the lever is moved inwardly actuating the lever 37 and causing the brake shoes 39 to contact with the brake drum 9. Thus when the regulator draws the wheel out of the face of the wind, the brake is simultaneously applied to hold the wheel inoperative.

In addition to the foregoing I provide manual means for moving the wind wheel 4 into inoperative position and this means will now be described. Upon the shaft 27 in front of the casing 1 is disposed a collar 40^a loose on said shaft and formed with a laterally projecting lever arm 41, said arm having connected thereto one end of a spring 42, the other end of which is connected to the casing as indicated at 43. In one face of the collar is formed a groove 44 into which projects a pin or stud 45 extending laterally from a set collar 46 carried by said shaft adjacent to the collar 40^a, the set collar 46 being held fast on the shaft as by means of the set screw 47. The arm 41 has connected thereto a flexible cable or wire 48 passing downwardly through the base of the casing 1 and connected at its lower extremity with a sleeve 49 loosely mounted upon the pump or connecting rod 50, which latter is connected to a swivel 51, to which in turn

the pitman 18 hereinbefore mentioned is connected at its lower end. Pivotedly mounted upon one leg of the tower 24 at 52 is a lever 53 the inner end of which carries a collar 54 surrounding the sleeve 49 and to this arm 53 is connected a pull wire or operating member 55, passing downwardly to a convenient point of access at the base of the tower. It will thus be apparent that when it is desired to render the wind wheel 75 inoperative, the operator pulls upon the cable 55 drawing the sleeve 49 downwardly and actuating the connecting member 48 so as to pull the lever arm 41 and its collar against the tension of the spring 42, said collar through its connection with the collar 46 rotating the shaft 27 and raising the rudder 25 to the horizontal position indicated by Fig. 1. The wheel is thus turned out of the wind by the overbalancing action hereinbefore mentioned and the brake applied to prevent its rotation.

Having thus described my invention, what I claim as new is:

1. In a wind mill, the combination of a wind wheel, a rotatable support therefor, controlling means for moving the wheel into and out of operative position and comprising a vane depending below the wheel axis and normally disposed adjacent to the axis of rotation of the revolute support, and counterbalance means operably connected to the vane and normally disposed parallel with the vane, said vane being movable upwardly in an adjacent parallel plane with the wheel by abnormal wind pressure into a position with its longitudinal axis at right angles to the axis of the support whereby to cause the wheel to move into inoperative position.

2. In a wind mill, the combination of a wind wheel, a revolute support therefor, controlling means for moving the wheel into and out of operative position comprising a vane pivotally mounted on said support below the axis of the wheel and normally arranged in a vertical plane parallel with the axis of rotation of the revolute support, said vane being movable upwardly in a plane parallel with the wind wheel by abnormal wind pressure into a horizontal position with its longitudinal axis at right angles to the axis of the revolute support aforesaid whereby to cause the wheel to move into inoperative position, and means for adjusting the angularity of said vane to regulate its operation by wind pressure.

3. In a wind mill, the combination of a wind wheel, a revolute support therefor, a rudder adapted to control movement of said wind wheel, a shaft carried by said support, means connecting the rudder with said shaft, brake means for said wheel including a brake lever adjacent to the connecting means, said lever being provided with a cam

extremity, and means on the connecting means aforesaid operable upon actuation of the rudder to impinge the cam extension and apply the brake.

5 4. In a wind mill, the combination of a wind wheel a revoluble support therefor, a rudder for controlling movement of said wheel, a shaft journaled in said support, a gear member fast to said shaft with which 10 said rudder is connected, a projection extending from said gear member, and brake means for said wheel including a brake lever lying in the path of movement of said projection and adapted to be impinged by said 15 projection for applying the brake.

5. In a wind mill, the combination of a wind wheel a revoluble support therefor, a rudder for controlling movement of said wheel, a shaft journaled in said support, a 20 gear member fast to said shaft with which said rudder is connected, a projection extending from said gear member, brake means for said wheel including a brake lever lying in the path of movement of said projection and adapted to be impinged by said 25 projection for applying the brake, means normally holding said brake released, a second shaft journaled in said support adjacent to the first-mentioned shaft, a gear member on the second mentioned shaft meshing with the gear member for said rudder, and a counter- 30 balance means on said second mentioned

gear member for normalizing the rudder aforesaid.

6. In a wind mill, the combination of a 35 wind wheel, a rudder for controlling movement thereof, an axle to which said rudder is fixed, manual means for moving said rudder into position for rendering the wind wheel inoperative, said means comprising a 40 lever loosely carried by said axle, and means on said axle with which said lever coacts for actuating the axle and thereby the rudder.

7. In a wind mill, the combination of a 45 wind wheel, a rudder for controlling movement thereof, a pivotal support for said rudder, manual means for moving said rudder on its support into position rendering the wind wheel inoperative, said means comprising a lever, a collar to which said lever is 50 connected and mounted upon the rudder support, a set collar adjacent thereto and rigid with said support, interlocking means between the collars for operatively connecting the lever for actuation of said support, 55 and an operating member connected to said lever.

In testimony whereof I affix my signature in presence of two witnesses.

ALFRED CARLSON.
